Primary Examiner — Philip S Hyder*Assistant Examiner* — Keith Frank(74) *Attorney, Agent, or Firm* — James R. Gourley; Colin P. Cahoon; Carstens & Cahoon, LLP**CLAIM**

The ornamental design for a cup, as shown and described.

DESCRIPTION

FIG. 1 is a first perspective view of the cup;

FIG. 2 is a front elevation view of the cup;

FIG. 3 is a side elevation view of the cup;

FIG. 4 is an opposite side elevation view of the cup;

FIG. 5 is a rear side elevation view of the cup;

FIG. 6 is a (top) plan view of the cup showing a series of inward extending protrusions forming a circumferential array;

FIG. 7 is a bottom plan view of the cup;

FIG. 8 is a second perspective view of the cup (from below); and,

FIG. 9 is a vertical cross sectional view of the inside of the cup, taken along plane 9-9 of FIG. 6.
